UNITED STATES PATENT OFFICE.

BENJAMIN D. GULLETT, OF AMITE CITY, LOUISIANA, ASSIGNOR TO THE
GULLETT GIN MANUFACTURING COMPANY, OF SAME PLACE.

IMPROVEMENT IN COTTON-GINS.

Specification forming part of Letters Patent No. 140,365, dated July 1, 1873; reissue No. 6,035, dated
September 1, 1874; application filed February 26, 1874.

DIVISION B.

To all whom it may concern:

Be it known that I, BENJAMIN D. GULLETT, of Amite City, in the parish of Tangipahoa and State of Louisiana, have invented a new and useful Improvement in Hoppers for Cotton-Gins; and I do hereby declare that the following is a full, clear, and exact description thereof, reference being had to the accompanying drawing making part of this specification, in which the drawing represents a vertical longitudinal section of a portion of a cotton-gin, the section being taken at a right angle to the shaft of the gin-saws.

My invention relates to an improved construction of the roll or ginning box, in which the cotton is fed to saws, which extend through the ribbed breast of a cotton-gin.

To enable others skilled in the art to make and use my invention, I will proceed to describe it.

A represents a part of a cotton-gin, which is properly housed in. B is the hopper; C, the ginning-saws; and D, the ribbed breast, through which the saws work. The hopper B is hinged, as usual, at its upper end, so that it can be turned up when it is desired to obtain access to the gin-saws. The inner surface of the hopper on the front side is formed of segments of two ellipses struck from different points. The elliptical segment b terminates near the middle of the vertical depth of the hopper, and is united with the segment b', which cuts back farther into the front board of the hopper by means of a horizontal shoulder, a. The segment b' extends down from the back of this shoulder in a forward direction nearly to the teeth of the saws. The two segments are so struck that, if the upper one were continued down to the point x, it would just about unite with the lower terminus of the segment b', and, if the segment b were continued up to the point y, it would just about

unite with the upper terminus of the segment b. By this means the roll of cotton runs down on the segment b to the shoulder a, and receives its necessary turn or direction toward the saw, and from that point descends with less friction toward the point x, where it is caught by the saws, thus insuring very perfect feeding of the cotton to the saws. The back board of the hopper is curved at c, and may be regarded as a shorter segment of an elliptical figure. This curved portion rests down upon the top or shoulder d of the concave portion e of the ribs of the breast. The base of this part stands back of the shoulder d of the breast, and by this means the cotton is prevented from rising too high, as the saws press it upward through the ribbed breast, and the rolls have a direction toward the front part of the hopper in case they should slip away from the saw-breast.

It will be observed that the upper surface b curves so as, with the surface c, to contract the mouth of the hopper, while the surface b' recedes, at the shoulder a, from the gin-saws, and thereby increases the area between the front board and the saws, giving greater room for the rolls to move in as they travel to the point x, where the saws take hold of them.

The curves of the interior of the hopper may be varied slightly so long as the shoulder a is maintained.

What I claim as new is—

The cotton-gin hopper constructed with the surfaces b b', the shoulder a, and the concave surface c, for reducing friction upon the cotton in its passage to the ribs and saws, substantially as set forth.

BENJAMIN DAVID GULLETT.
